UNITED STATES PATENT OFFICE.

GEORGE H. CARLON, OF OSKALOOSA, IOWA.

DESIGN FOR A HEAD FOR LAWN-SPRINKLERS.

SPECIFICATION forming part of Design No. 33,917, dated January 15, 1901.

Application filed December 11, 1900. Serial No. 39,551. Term of patent 7 years.

To all whom it may concern:

Be it known that I, GEORGE H. CARLON, a citizen of the United States, residing at Oskaloosa, in the county of Mahaska and State of Iowa, have invented and produced a new and original Design for Heads for Lawn-Sprinklers, of which the following is a specification, reference being had to the accompanying drawings, forming part thereof, in which—

Figure 1 is a perspective view of a lawn-sprinkler head constructed in accordance with my design, and Fig. 2 a top plan view of the same.

As shown in the drawings, the leading or material feature of my design consists of a lower portion A, having its walls inclined downwardly and inwardly and terminating in a stem B, which is round in cross-section. At the upper end of the lower portion A is positioned an upper portion C, having its walls inclined upwardly and inwardly and having its top portion flattened, as illus-

trated at D. The said upper portion is provided in its flattened top with a series of openings E, which are arranged in a circle, 25 and with an opening F arranged at the center of said circle of openings. Near the flattened top the upper portion C is provided with a series of openings G, extending entirely around its circumference, and has the 30 remainder of its surface below said perforations G formed with rows of perforations H of larger size than the perforations G and so arranged that the perforations of one row alternate those of the adjacent row. 35

Having described my invention, what I claim as new, and desire to secure by Letters Patent, is—

The design for a lawn-sprinkler head, substantially as herein shown and described. 40
GEORGE H. CARLON.
